UNITED STATES PATENT OFFICE.

JOHN R. SUNDEE, OF BUFFALO, NEW YORK, ASSIGNOR TO EMPIRE JEWELRY CASE COMPANY,
OF BUFFALO, NEW YORK, A CORPORATION OF NEW YORK.

DESIGN FOR A JEWELRY-CASE.

No. 39,311.

Specification for Design.

Patented May 19, 1908.

Application filed December 23, 1907. Serial No. 407,853. Term of patent 7 years.

To all whom it may concern:

Be it known that I, JOHN R. SUNDEE, a citizen of the United States, residing at Buffalo, in the county of Erie and State of New York, have invented a new, original, and ornamental Design for Jewelry-Cases, of which the following is a specification, reference being had to the accompanying drawing, forming part thereof.

The figure is a perspective view of a jewelry case, showing my new design.

I claim:

The ornamental design for a jewelry case, as shown.

JOHN R. SUNDEE.
